UNITED STATES PATENT OFFICE.

JOHN WESLEY WHITE, OF BUTTE, MONTANA.

TIE MOUNT AND CARRIER.

Application filed June 18, 1924. Serial No. 720,850.

To all whom it may concern:

Be it known that I, JOHN WESLEY WHITE, a citizen of the United States of America, residing at Butte, in the county of Silver bow and State of Montana, have invented certain new and useful Improvements in Tie Mounts and Carriers, of which the following is a specification.

This invention relates to an improved neck tie mount and carrier, constructed of wire and arranged to provide a mount by which a particularly desirable and adaptable form is given to the tie, and a carrier, in the use of which the tie, as arranged on the mount, is held properly in place in all types of fold collars, and particularly soft collars of this type with a perfect simulation of the tie extending around the collar in the usual manner.

The improved tie mount and carrier is made up of various parts connected in a uniform whole with the various parts resiliently connected to insure a power set of the carrier with regard to any particular collar with which it may be used without inducing strain on any portion of the collar and in the mount portion to hold the knot of the tie under more or less tension to insure a smooth, even, and uniform appearance.

The invention is illustrated in the accompanying drawings, in which:

Fig. 1 is a view in front elevation showing a tie of the four-in-hand type in position on the tie mount and carrier.

Fig. 2 is a rear elevation of the same.

Fig. 3 is a front elevation of the tie mount and carrier constructed in accordance with this invention.

Fig. 4 is an edge view of the same.

Fig. 5 is a vertical central section of the same.

Fig. 6 is a broken elevation, the forward portion of the tie mount being omitted.

Fig. 7 is a similar view with the tie mount entirely omitted.

Fig. 8 is a broken rear elevation showing the collar button engaging member slightly extended to cooperate with soft collars for holding the tie higher in the collar.

Fig. 9 is a broken elevation showing particularly the tie band extension.

The improved tie mount and carrier is constructed of a single length of wire which is formed to present depending V-shaped

legs 1 and 2, formed of divergent strands, with the inner strand of sinuous form at 3, and said inner strands connected at their upper ends by a coil 4 of a single wire 60 length crossing at the upper end of the coil. These legs 1 and 2 form the means for attaching the tie mount and carrier to the button of the ordinary fold collar, the spring coil 4 permitting a spreading of the 65 legs as may be necessary and insuring their proper grip upon the collar button. The terminals of the legs are preferably turned slightly outwardly and forwardly to insure easy application of the tie mount and carrier to a button without catching into the buttonhole of the collar or meeting other obstruction. The outer strands of the legs 1 and 2 are projected laterally at 5 and such lateral extensions are terminally pro- 75

jected downwardly at 6 and formed into return bends 7 and projected upwardly to form tie band engaging sections 8. These tie band engaging sections 8 are adapted to receive the loops of the tie in both direc- 80

tions beyond the knot, as will later appear, and serve to hold the band portion of the tie extended in both directions beyond the knot to simulate the effect of the band passing around the collar. Beyond the tie band sections 8, the material of the improved tie 85

mount and carrier is carried upwardly and outwardly at 9 to form collar extensions, these extensions including return bend lengths 10 and slightly divergent relative to the lengths 9. The return lengths 10 of the collar extensions are projected toward the lateral lengths 5 and are formed in part 90

of portions 11 which are more or less in parallelism with the tie band engaging sections 8. The portions 11 are projected to and coiled at 12 loosely about the lateral lengths 5, the material being extended be- 95

yond the coils toward the collar button engaging portion by means of lengths 13 100 which diverge with respect to the lengths 5 from the coil connections 12. The terminals of the lengths 13 are utilized to form the tie mount proper, and these lengths 13 are substantially in line with the collar but- 105

ton engaging member projected downwardly and forwardly at 14, being intertwined at 15 to form an appropriate length of tie mount, the intertwined portions being then extended in opposite directions in return 110 bends 16 carried upwardly in parallelism with the sections 14 and coiled about the

lengths 13, near the ends of the latter, as at 17. From the coils 17, the material is carried downwardly to provide a length 18, which inclines forwardly and downwardly 5 with respect to the normal plane of the tie mount and carrier but at a less inclination than the lengths 14. The lengths 18 terminate on a plane slightly above the lower ends of the legs 1 and 2 in forwardly 10 projecting loops 19, the return sections of which loops extend upwardly as lengths 20 in slightly divergent relation to the length 18, the terminals of the lengths 20 being coiled about the lengths 13 as at 21 immediately adjacent the juncture of the lengths 13 with the lengths 14.

It is to be noted that the tie mount is made up of the lengths 14 and 16, which form a forwardly projecting portion in 20 substantial transverse alignment, the tie mount also including the rear sections made up of the lengths 18, loops 19, and lengths 20, and that the sections making up this tie mount proper have, by reason of their coil 25 connection about the lengths 13, a relative resiliency, which when the neck tie is looped about said sections when forming the knot, tend to exert a spreading tension on the knot to maintain it in even smooth condition during use. The tie band engaging sections 8 have, by reason of the coil 4, and the resili- 30 ent relation of the portions of the legs 1 and 2, a more or less resilient relation one to the other, that is, these sections may be moved 35 slightly toward each other against the spring resistance of the parts and tend to spread when this pressure is relieved. As these tie band engaging sections receive the loop of the band, it will be apparent that 40 said tie band engaging sections will be in effect stretched following their application to the tie mount and carrier so as to hold the band portions of the tie which project on opposite sides of the knot in a smooth even condition. The collar extensions formed of 45 the lengths 9 and 10 are of course resilient due to their formation, and may be thus caused to engage beneath the outer fold of a fold collar and readily accommodate them- 50 selves to the particular character of this fold without strain,

In forming a tie on the tie mount and holder, the tie is passed rearwardly of the tie mount and between the same and the collar button engaging portion and in front of the sections 11, back of the sections 8, and then forwardly toward the tie mount. The smaller end of the tie is passed beneath the tie mount but in front of parts 18 and 20, while the larger end of the tie in which the knot is to be formed is passed around the tie mount, that is, over the lengths 14 and 16 and in rear of the lengths 18 and 20, and again carried forwardly over the lengths 14 60 and 16 and the free end passed upwardly 65

between the lengths 5 and 13, that is, forwardly of the lengths 5 and rearwardly of the lengths 13. This portion of the tie is then passed down through the second loop portion over the tie mount, forming the 70 usual four-in-hand knot, as shown in Fig. 1. When thus applied, it will be apparent that from the face view, the entire tie mount and carrier is concealed, except the collar extensions, including the lengths 9 and 10, while 75 from the rear view, the collar button engaging portion and the lengths 5 are exposed. The knot indicated at 22, is formed entirely on the tie mount, and by reason of the downward and forward inclination of the latter, 80 the tie is held at a slight inclination to the shirt front and collar, which is highly desirable in neck ties of this type. Furthermore, the knot proper is held under tension 85 by the resiliently connected front and rear portions of the tie mount, and thus the knot is always maintained under sufficient tension to insure it retaining its form. Those sections of the tie band which extend beyond the knot and embrace the tie engaging sections 8 are also resiliently held by the spreading action of these tie band engaging sections so that these tie band extensions indicated at 23, are stretched in an even 90 smooth manner to simulate the appearance 95 of the tie band extending around the collar when the device is applied. Obviously, the structure is connected in place by engaging the collar button between the legs 1 and 2, causing the button to seat approximately 100 adjacent the spring coil 4. The collar engaging extensions including the lengths 9 and 10 are passed between the folds of the collar, serving to accommodate the tie 105 mount and carrier to the shape of the collar, in causing the parts connected with these collar extensions to follow the bending of these extensions as they ride into contact with the collar fold. In this action, the following spring portions of the tie mount and carrier yield to insure a proper set of the device without distortion, that is to say, coil spring 4, the V-shaped spring leading from 110 13 to about one-third the length of 14, lateral lengths 5 and 13 combined, coils 12 115 around 13, lengths 1 and 2, lower parts of 5, and sections 8, 9 and 10. Of course the tie band engaging sections 8 are located a sufficient distance from the knot to carry the band portions 23 of the neck tie beyond the 120 collar opening, thus simulating extending the band entirely around the collar.

In Fig. 8, a slight modification is provided, adapting the improved tie mount and carrier more particularly for use with soft collars, wherein it is highly desirable that the knot of the tie should be arranged closely to the fold of the collar, in order to properly support the collar in front above the collar button. For this purpose, the modified con- 125 130

struction involves simply an extension of the neck tie engaging portion, such neck tie engaging portion 24 being formed at the lower end of an intertwined portion 25, 5 which at the upper end is projected to form the lateral lengths 5 of the usual form, one of the strands however, prior to its projection as a lateral length 5, being formed into a spring coil 26 corresponding to and having the function of the spring coil 4.

The device is preferably constructed of spring wire, though obviously any appropriate material may be used, and the various sections, constructed as an integral whole, 15 are yet so independently resilient as to insure the best results in holding the knot in a proper form and shape, projecting the band portion beyond the knot in proper form and shape and holding the entire structure beneath the fold of the collar to insure conformity with the size and shape of the collar.

Claims:

1. A tie mount and carrier constructed of wire and formed to provide a tie mount to permit the formation of a knot thereon, said tie mount involving resiliently connected front and rear sections the sections being mounted for relatively resilient connection 25 and the rear section being formed to provide relatively lateral resiliency, whereby the tie mount is adapted to exert pressure in at least two independent directions on the knot.

2. A tie mount and carrier constructed of wire and formed to present a resilient tie mount on which the knot is to be formed, and resilient band engaging sections disposed in opposite directions beyond the tie mount to engage beneath the collar, said sections being formed in part to receive and resiliently hold loops of the band of the tie in the use of the tie mount and carrier.

3. A tie mount and carrier constructed of

wire and formed to present a resilient tie mount on which the knot is to be formed, 45 and resilient band engaging sections disposed in opposite directions beyond the tie mount, said sections being adapted to receive and resiliently hold loops of the band of the tie in the use of the tie mount and 50 carrier, said tie mount and carrier including resilient outwardly and rearwardly disposed extensions to engage beneath the fold of the collar.

4. A tie mount and carrier, comprising 55 collar button engaging portion and extending laterally to and in opposite directions therefrom, spaced lengths arranged in the plane of said collar button engaging portion, a tie mount resiliently connected to one of 60 said lengths, and tie band engaging portion carried by the other of said lengths.

5. A tie mount and carrier, comprising a central portion made up of inwardly divergent lengths, one of said lengths being 65 formed to provide a collar button engaging portion, the other of said lengths being formed to provide a tie mount, said inwardly divergent lengths being connected together in opposite directions beyond the 70 tie mount and extended beyond said connected portion to provide collar engaging extensions which are in part formed to provide tie band engaging portions.

6. A tie mount and carrier, comprising a 75 central portion forming collar engaging members and band engaging sections, and a tie mount comprising resilient front and rear sections integral with the central portion, with the rear sections having resilient so sliding connection with the central portion, all parts being resiliently formed and connected to permit yielding under such resiliency as the device is applied to the collar.

In testimony whereof I affix my signature.

JOHN WESLEY WHITE. [L.s.]
